FIRE EXTINGUISHER

Glenn G. Griswold and Floyd J. Lee, East Los Angeles, Calif., assignors to J. Leonard Hull, Los Angeles, Calif.

Application August 11, 1941, Serial No. 406,278

9 Claims. (Cl. 169—32)

Our invention relates to fire extinguishers, such as portable types now in use, although it is not limited thereto.

One of the principal objects of this invention is to provide a fire extinguisher having separate chemicals to be mixed with a liquid solvent, and in which the chemicals are contained in separate sealed receptacles of novel construction and novel arrangement relative to each other so that they may be readily and simultaneously opened or ruptured and the contents thereof emptied or deposited into the solvent.

Another important object of this invention is to provide novel means for readily opening or rupturing a plurality of receptacles within a pressure container from the outside of the latter for emptying or depositing the contents of the receptacles into a solvent in the container.

An important object also is the provision of a fire extinguisher, having a novel cartridge for holding in separated and sealed condition several chemicals, for the operation of the fire extinguisher, and also for holding the means for opening, severing, or rupturing the receptacles for such chemicals.

A further important object of this invention is the provision of a fire extinguisher, all loose, movable, or removable parts of which may be easily and effectively sealed so that it may not be easily tampered with or operated by unauthorized persons without breaking the seal, and further that it may be readily inspected to determine whether it has been tampered with or operated.

A still further object of this invention is the provision of a fire extinguisher which is simple and economical of construction proportionate to its functions, and simple and economical to refill and operate, one in which the chemicals will not readily deteriorate, and, therefore, to provide a long-life fire extinguisher which need not often be renewed or inspected.

Still another important object of this invention is to provide means or elements so constructed that they may be embodied or substituted in a conventional fire extinguisher for readily converting the same into a fire extinguisher incorporating our improvements.

An important object also of our invention is to provide a novel refill cartridge for a fire extinguisher, and one which may be readily installed by the ordinary person.

With these and other objects in view, as will appear hereinafter, we have devised a fire extinguisher having certain novel features of construction, combination, and arrangement of parts

and portions, as will be hereinafter described in detail and particularly set forth in the appended claims, reference being had to the accompanying drawing and to the characters of reference thereon, which form a part of this application, in which:

Fig. 1 is a side elevation of a fire extinguisher embodying the various features of our invention, portions being shown broken away and in section to facilitate the illustration;

Fig. 2 is an enlarged sectional view showing particularly the chemical containing cartridge therefor, parts of the container being also shown broken away and in section to facilitate the illustration;

Figs. 3, 4, 5, and 6 are transverse sectional views thereof taken respectively through 3—3, 4—4, 5—5, and 6—6 of Fig. 2;

Fig. 7 is a top view of our fire extinguisher;

20 Figs. 8 and 9 are enlarged sections taken through 8—8 and 9—9 of Fig. 1, showing particularly the relation of the sealing means to parts of our fire extinguisher; and,

Fig. 10 is an enlarged view of the nozzle end 25 of the fire extinguisher.

Our fire extinguisher may be similar in appearance to the portable extinguishers now in use, except as hereinafter described. It is enclosed in a main container or tank 1, having a discharge 30 hose 2, which is provided at its free end with a nozzle 3, and is connected at its other end to an outlet 1^a at the upper portion of the container or tank 1, by means of a fitting 4. At the upper end of the container 1 is a filling opening 1^b, 35 which is closed by a ring screw cap or plate 5 having a ring or handwheel 5^a to facilitate the turning of the cap or plate.

Within the container is stored a supply of solvent 11, which in this instance is water.

40 At the upper end of the container 1 are suspended the chemicals which are to be mixed with the water to form the fire extinguishing agent. These chemicals are contained in a cartridge A, which is carried by, and suspended from the cap 5, all of which is shown best in Fig. 2. The lower end of the cartridge extends below the surface of the water 11, and the cartridge is so arranged in the container 1, that it may be easily removed and replaced by another.

45 The cartridge consists essentially of a readily destructible or shatterable cylindrical tube 22, in which are placed chemicals 23 and 24 and a tube-breaking device 25, which is actuated, for breaking the tube, by an operating member 26. The 50 tube 22 is preferably made of glass and has a

closed bottom end; the upper end is hermetically sealed with a glass or similar stopper 29, which may be cemented in place. The stopper has a central hole at the upper end for receiving the lower end of the plunger 30, whereby the upper end of the tube 22 is centrally located. The chemical 23 may be sodium bicarbonate (NaHCO_3), and the chemical 24 may be oxalic acid ($\text{H}_2\text{C}_2\text{O}_4 \cdot 2\text{H}_2\text{O}$), both in dry powdered form, the former occupying the lower end portion of the tube and the latter the upper portion. These chemicals are separated, and contained in hermetically sealed compartments within the tube 22, by a readily destructible wad or wall 27, which may be paraffin. The upper portion of the chemical 24 is protected by another wad or wall 28 of paraffin.

The tube breaking device 25 is shown as consisting of a pair of bars 25^a and 25^b, which are preferably parallel and pivotally connected by links 25^c and 25^d, which also may be parallel. This breaking device is enclosed in the tube with the links at an angular position. Such position of the links 25^c and 25^d moves the bars 25^a and 25^b close together, and the wads 27 and 28 temporarily hold the bars in such position.

The bars 25^a and 25^b are so arranged that longitudinal movement of one bar with respect to the other will cause the bars to be separated in order to break the tube 22 outwardly from within.

For the purpose of performing such function, the lower end of the bar 25^a is enlarged or bifurcated, as indicated by 25^e, and this enlarged portion is positioned in engagement with the bottom of the tube. The upper end of the bar 25^b is bent laterally to form an anvil, as indicated by 25^f. This anvil is positioned in the path of a plunger 30, which is reciprocally mounted in the axial portion of the cap 5. The lower end of the plunger is preferably separated from the anvil or arm 25^f by the stopper 29, as referred to above.

In the axial portion of the cap 5, which may be similar to the corresponding cap of the conventional fire extinguisher, is screwably mounted a sleeve 31, which is held in place by a lock nut 32 seated against the inner side of the cap 5. The plunger 30 is reciprocally mounted in this sleeve. To the portion of the upper end of the sleeve 31, which extends above the cap 5, is screwed a stuffing box member 33, through which also extends the plunger 30.

The outer or upper end of the stuffing box member is bifurcated, forming ears 33^a, between which is pivotally mounted the operating member 26, which in this instance is a lever. At the pivoted portion of the lever 26 is provided a cam 26^a for forcing the plunger 30 inwardly when the free end of the lever 26 is raised.

The tube 22 is encased in a perforated metal casing or wire mesh basket 41, the upper end of which is permanently secured to the inner end or underside of the cap 5. The opposite, or bottom, end of the basket 41 is closed by a hinged or otherwise removable cover 42. This cover is closed against the inner end of the tube 22, but is separated therefrom by a resilient member 43, which may be a spring, as shown, or other resilient rest.

The perforate basket permits the chemicals, when the tube 22, or chemical receptacles, is ruptured, to be deposited into the water, or the water to enter the basket to dissolve the chemicals. The basket also retains the broken glass

of the tube so that all of the broken glass may be removed when the cartridge is replaced.

When the plunger is forced inwardly against the stopper, the stopper is forced downwardly, tending to crush the tube 22, forcing the bar 25^b downwardly and thereby forcing or shattering outwardly the side walls of the tube 22.

In order to prevent unwarranted or unauthorized tampering or operation of the fire extinguisher, we have provided an effective sealing means for the various operating parts, which might be removed or damaged intentionally or otherwise to prevent their normal operation when desired or necessary.

One seal device, designated 51, consists of a sealing wire, the ends of which are secured together by an authorized molded metal seal 51^a, which may be readily ruptured. The wire of this sealing device extends through or between the spokes of the ring or handwheel 5, an eye 26^b intermediate the ends of the lever 26, and through a hole 52^b in the threaded end of the bolt 52^a, which holds the clamp 52 in position. The nut 52^c for the bolt 52^a may be a castellated nut, and the portion of the sealing wire 51 which is threaded through the hole 52^b also passes through aligned slot in the nut 52^c to prevent the turning of the latter relative to the shank of the bolt.

The clamp 52 may be a band or hose clamp for securing the inner end of the hose 2 to the fitting 4, or it may be a suitable band or clamp secured over the permanent or crimped hose fastening means in common use, as shown.

Another sealing device 53 is provided at the nozzle end of the hose. This device also consists of a sealing wire, the ends of which are secured together by a conventional molded metal seal 53^a, which may be readily ruptured when the nozzle is forceably removed.

A part of the latter sealing device consists of a wire arm 54, which is secured at one end to the side of the container, or to a place secured thereto. The other end of the arm is bent up, as indicated by 54^a. This upwardly turned portion enters the discharge opening of the nozzle 3 when the latter and the hose are in their normal inoperative position. The sealing wire 53 is threaded through an eye or loop 54^b in the arm 54, and a hole 55^b at the end of a bolt 55^a, which secures the hose clamp 55 in position, the hose clamp being employed in this instance to secure the hose 2 to the inner end of the nozzle 3, as shown in Figs. 1 and 9. The bolt 55^a, also has a castellated nut 55^c, certain slots of which are also adapted to be aligned with the hole 55^b. The sealing wire which is threaded through the hole also passes through such aligned slots to prevent the nut from turning.

The clamp 55, also, may be a hose clamp for securing the hose 2 to the nozzle 3, or it may be a suitable ring or other means secured over the permanent or crimped hose fastening means in common use, as shown.

Thus, all of the necessary and operating parts are effectively sealed against tampering and unauthorized use. Tampering with these seals may also be readily observed by only casual inspection.

The bent up arm 54^a substantially closes the nozzle opening and thereby prevents insects or other animals from entering the hose or nozzle.

Though we have shown and described a particular construction, combination, and arrangement of parts and portions of our fire extinguisher, we do not wish to be limited to the same,

but desire to include in the scope of our invention the construction, combination, and arrangement, substantially as set forth in the appended claims.

We claim:

1. A fire extinguisher, comprising a pressure container having an opening, said container being adapted to contain a solvent, a cap for the opening, a plurality of axially aligned receptacles supported by the cap in the container, a different gas-forming chemical in each receptacle, said chemicals being capable of reacting with the solvent to create a gas, and means extending beyond the cap and into each of the receptacles for rupturing all of the latter, said means comprising a pair of spaced bars positioned in all of said receptacles, means for forcing said bars apart for breaking said receptacles from within, an operating member extending through the cap for actuating the last mentioned means.

2. A fire extinguisher, comprising a pressure container having an opening, said container being adapted to contain a solvent, a cap for the opening, a plurality of axially aligned receptacles supported by the cap in the container, a different gas-forming chemical in each receptacle, said chemicals being capable of reacting with the solvent to create a gas, and means extending beyond the cap and into each of the receptacles for rupturing all of the latter, said means comprising a pair of spaced substantially parallel bars, links pivotally connecting the bars, one of the bars engaging the bottom of the lowermost receptacle and the other bar extending upwardly toward the cap, and an operating member extending through the cap for forcing the last mentioned bar downwardly, and thereby forcing said bars apart for breaking said receptacles from within.

3. A fire extinguisher, comprising a pressure container, a plurality of axially aligned receptacles supported in the container, a different chemical in each receptacle, and means within the container and extending into each of the receptacles, said means comprising a pair of spaced bars positioned in all of said receptacles, means for forcing said bars apart for breaking said receptacles from within, and an operating member extending into said container from without for actuating the last mentioned means.

4. A fire extinguisher, comprising a pressure container, a plurality of axially aligned receptacles supported in the container, a different chemical in each receptacle, and means within the container and extending into each of the receptacles, said means comprising a pair of spaced substantially parallel bars, links pivotally connecting the bars, one of the bars engaging the bottom of the lower-most receptacle and the other bar extending upwardly toward the cap, and an operating member extending into said container from without for forcing the last mentioned bar downwardly, and thereby forcing said bars apart for breaking said receptacles from within.

5. A fire extinguisher, comprising a container having an opening, a removable cap for the opening, and a chemical-containing cartridge within the container, said cartridge being attached to the inside of the cap, said cartridge being insertable through the opening into the container while attached to the cap, said cartridge containing different hermetically sealed chemicals, and means extending through the cap for releasing the chemicals from the cartridge into the container.

6. A fire extinguisher, comprising a pressure container having an opening, a cap for the opening, a receptacle supported by the cap within the container, a chemical adapted to be contained in the receptacle, and means extending beyond the cap and into the receptacle for rupturing the same, said means comprising a pair of spaced bars positioned in said receptacle, means for forcing said bars apart for breaking said receptacle from within, and an operating means extending through the cap for actuating the last mentioned means.

7. A fire extinguisher, comprising a pressure container having an opening, a cap for the opening, a receptacle supported by the cap within the container, said receptacle adapted to contain a chemical, and means extending beyond the cap and into the said receptacle for rupturing the same, said means comprising a pair of spaced substantially parallel bars, links connecting the bars, one bar engaging the bottom of the receptacle, the other bar extending upwardly toward the cap, and an operating member extending through the cap for forcing the last mentioned bar downwardly and thereby forcing said bars apart for breaking said receptacle from within.

8. A fire extinguisher, comprising a pressure container, a receptacle supported in the container, a chemical adapted to be contained in the receptacle, and means for rupturing said receptacle, said means comprising a pair of spaced bars positioned in said receptacle, means for forcing said bars apart for breaking said receptacle from within, and an operating member extending into said container from without for actuating the last mentioned means.

9. A fire extinguisher, comprising a pressure container, a receptacle supported in the container, a chemical adapted to be contained in the receptacle, said means comprising a pair of spaced substantially parallel bars, links pivotally connecting the bars, one of the bars engaging the bottom of the receptacle, and the other bar extending upwardly beyond the top of the receptacle and toward the top of the container, and an operating member extending into said container from without for forcing the last mentioned bar downwardly and thereby forcing said bars apart and breaking said receptacle from within.
